CYRENUIS H. SMITH AND JOSEPH ADAMS, OF BUTTE, MONTANA.

BOWLING-ALLEY BALL.

No. 838,026.

Specification of Letters Patent.

Patented Dec. 11, 1906.

Application filed April 20, 1906. Serial No. 312,904.

To all whom it may concern:

Be it known that I, CURTIS HOLLAND, a citizen of the United States, residing in Butte, county of Silverbow, State of Montana, have invented a certain new and useful Improvement in Bowling-Alley Balls, of which the following is a specification.

The elimination of the ancient crudities and the most undesirable features of the 10 bowling-alley ball of the present day has brought out many methods and manners calculated to be beneficial; but the suggested improvements have so far failed to a certain extent in overcoming unnatural strains due 15 to the handling and delivery of the ball. For centuries a solid ball of stone was used, which later was substituted by one of solid wood. The next improvement was the boring of finger and thumb holes, providing for 20 a much better grip for the hand and a greater control over the delivery of the ball. However, the finger-holes still leave much to be desired, since they disturb somewhat the balance and also break the spherical surface 25 of the ball. Since there is great variation both in size and spread of different human hands, it is essential that provision be made to accommodate many, thus necessitating an unwarranted expense in the manufacture 30 of the balls and also greatly adding to the stock and cost of outfitting a bowling-alley. The finger-holes quite often cause severe strains to the fingers and especially to the thumb and, further, produce unsightly calluses and sores which are slow in healing, thus depriving one from the enjoyment of 35 the game for days and even weeks at a time. The main object of this invention is to overcome the unnatural strains incident with 40 the use of the finger-holes and other forms provided for the manipulation of a bowling-alley ball and to provide means for obviating very materially an unnecessary discomfort most commonly experienced by bowlers. 45 Other objects are to provide for a bowling-alley ball having a perfectly smooth and unbroken surface, while still further providing means within itself for a freer and easier control and delivery of the ball. 50 To overcome the undesirable features found in the common bowling-alley ball, I provide a ball with an extensible and retractable spade-shaped handle, deeming it the most natural shape for the hand, while

presenting the least possible chance for causing soreness or injury in the handling and delivery of the ball. With a handle of this design the thumb is relieved of all strain, and the weight of the ball is supported by the several fingers of the hand as one would grasp 55 the handle of a satchel, and the ball may be delivered by the natural swing of the arm without necessitating the quarter-turn of the forearm, as required in delivering a ball having finger-holes. Gloves may be worn with 60 great satisfaction with a handle of this design, as they in no way interfere with the handling of the ball and, further, provide a sanitary feature appealing most especially 65 to women.

A bowling-alley ball constructed in accordance with my invention is shown in the accompanying drawings, in which—

Figure 1 is a vertical section showing the handle drawn out for use. Fig. 2 is a side 75 view of the handle, while Figs. 3 and 4 show cross-sectional and end views, respectively. Fig. 5 is a vertical section showing the handle as normally retracted and inclosed within the ball. Fig. 6 is a top plan view of a portion of the surface of the ball, showing the handle inclosed therein. Fig. 7 is a plan view of the lower portion of the ball, showing the spindle end and finger-button.

In the said drawings, 1 represents a bowling-alley ball having a countersunk rectangular-shaped chamber 6 at the top to conform with the rectangular-frame-shaped or spade-shaped handle 2, which is normally incased therein.

11, 12, and 13 represent a bore of different diameters extending downward from the rectangular-shaped chamber 6 and extending axially entirely through the remaining portion of the ball. This bore forms a chamber 95 for the reception of the handle-spindle 7 and for the spiral retracting-spring 8, one end of which bears against the shoulder 14, formed within the ball, while the opposite and lower end bears against the finger nut or button 9, secured to the lowermost end of the handle-spindle 7. This arrangement serves to normally retain the handle within the ball, as shown in Fig. 5, and also permits it to be drawn out by hand until the finger-button 100 9 comes in contact with the shoulder 15, also formed within the ball, which forms a stop to prevent the further outward movement of 105 110 115 120 125 130 135 140 145 150 155 160 165 170 175 180 185 190 195 200 205 210 215 220 225 230 the handle, as shown in Fig. 1. To enable the handle to be easily drawn out is the object of having the bore extend entirely through the ball and the bringing of the finger-button 5 9 approximately flush with the lower surface of the ball. A slight upward pressure of the finger on this button causes the handle 2 to emerge sufficiently to be grasped by the hand and readily pulled out against the re-tracting force of the spring 8, the strength of which need be only sufficient to insure the retraction of the handle before the ball comes in contact with the alley. In delivering the ball the handle as soon as it is released is 10 instantly retracted by the spring 8, thus avoiding any possibility of its coming in contact with the alley as the ball rolls thereover. A still further provision against injury to the 15 alley is attained by bushing the top of the handle 2 with rawhide, leather, or composition, as shown by 3. This bushing also serves to form a better grip for the hand, while at the same time lessening the weight at that end of the ball, which would otherwise be excessive were the handle made entirely of metal and would therefore greatly disturb the equilibrium of the ball. The 20 lower portion of the bushing 3 is dovetailed, as shown by 4, and fits into the dovetail slot 5 in the upper surface of the rectangular-frame-shaped handle 2. A little cement applied to the bushing before inserting it in the slot serves adequately to secure it therein, though it is obvious that both dovetailed 25 portions may be dispensed with and the bushing secured by other means—such, for instance, as by screws or rivets.

In Fig. 1 I have shown the spindle 7 as being a continuation of the rectangular-frame-shaped handle 2 and having a finger nut or button 9 either screwed or riveted to the lowermost portion of the said spindle. In Fig. 5 the spindle 7 and finger-button 9 are shown as one piece, which may be either screwed or riveted to the rectangular-frame-shaped handle 2, as desired. In Fig. 5 I also show that the bore 12 may be continued through to the rectangular-shaped chamber 6, providing that portion of the bore below the said chamber 6 with a bushing 16, the lower end of which serves as a bearing 14 for the re-tracting-spring 8.

As before stated, the finger nut or button 9 may be either screwed or riveted to the spindle 7, though it is preferable to use the former method, in which case both parts are provided with threaded portions.

In order to screw the finger nut or button 9 to the spindle 7 or for screwing the spindle 60 to the rectangular-frame-shaped handle 2, I provide the holes 10, as shown in Figs. 1 and 7, whereby a wrench adapted for the purpose may be inserted and the parts thus securely tightened.

It is obvious that the finger-button 9 may

be provided with a slot 17 like the eye of a screw, permitting thereby the use of a common screw-driver, which would be preferable to the holes 10 in case the spindle and button were of one piece, as shown in Fig. 5.

I am aware that changes in the form and proportions of parts and detail of construction may be made without departing from the spirit or sacrificing the advantages thereof, and I therefore reserve the right to make 75 all changes in the construction and arrangements of the parts of my improved bowling-alley ball which fall within the scope of my invention.

I am also aware of prior inventions providing for an extensible handle for bowling-alley balls, but know of none having the features and advantages heretofore described or the novel arrangements and inventions set out in the following claims.

Having thus fully described my invention, what I claim as new therein, and desire to secure by Letters Patent, is—

1. A bowling-alley ball having a hole extending axially entirely through said ball, the upper portion of said hole being of larger size and rectangular in shape.

2. A bowling-alley ball having a hole extending axially entirely through said ball, the upper portion of said hole being of larger size and rectangular in shape, while the lower and remaining portion of said hole forms a circular chamber or bore of different diameters.

3. A bowling-alley ball having an extensible and retractable member extending axially entirely through said ball.

4. A bowling-alley ball having an extensible and retractable member extending axially entirely through said ball, the upper portion of said member forming a handle of a rectangular-frame-shaped construction.

5. A bowling-alley ball having an extensible and retractable member extending axially entirely through said ball, the upper portion of said member forming a handle of a rectangular-frame-shaped construction having a dovetail slot in the said upper portion.

6. A bowling-alley ball having an extensible and retractable member extending axially entirely through said ball, the upper portion of said member forming a handle of a rectangular-frame-shaped construction having a dovetail slot, and a bushing secured to the uppermost portion of the handle and within the said slot.

7. A bowling-alley ball having an extensible and retractable member extending axially entirely through said ball, the upper portion of said member forming a handle of a rectangular-frame-shaped construction, while the lower and remaining portion of said member forms a shaft or spindle projecting downward from said rectangular-shaped portion.

8. A bowling-alley ball having an extensi-

ble and retractable member extending axially entirely through said ball, the upper portion of said member forming a handle of a rectangular-frame-shaped construction, while the lower and remaining portion of said member forms a shaft or spindle projecting downward from said rectangular-shaped portion, and a nut or button on the spindle.

5 9. A bowling-alley ball having an extensible and retractable member extending axially entirely through said ball, the upper portion of said member forming a handle of a rectangular-frame-shaped construction, while the lower and remaining portion of said member forms a shaft or spindle projecting downward from said rectangular-shaped portion, and having a nut or button on the spindle, and a spring encircling the spindle.

10 10. A bowling-alley ball having, in combination, a hole extending axially entirely through said ball, an extensible and retractable member extending entirely through and movable within the said hole, and means for normally retaining the said member within the ball.

15 11. A bowling-alley ball having, in combination, a hole extending axially entirely through said ball, the upper portion of said hole being of larger size and rectangular in shape, an extensible and retractable member extending entirely through and movable within the said hole, and means for normally retaining the said member within the ball.

20 12. A bowling-alley ball having, in combination, a hole extending axially entirely through said ball, the upper portion of said hole being of larger size and rectangular in shape, while the lower and remaining portion of said hole forms a circular chamber or bore of different diameters, an extensible and retractable member extending entirely through and movable within the said hole, and means for normally retaining the said member within the ball.

25 13. A bowling-alley ball having, in combination, a hole extending axially entirely through said ball, the upper portion of said hole being of larger size and rectangular in shape, while the lower and remaining portion

of said hole forms a circular chamber or bore 50 of different diameters, an extensible and retractable member extending entirely through and movable within the said hole, the upper portion of said member forming a handle of a rectangular-frame-shaped construction, and 55 means for normally retaining the handle within the upper rectangular-shaped portion of the hole.

14. A bowling-alley ball having, in combination, a hole extending axially entirely 60 through said ball, the upper portion of said hole being of larger size and rectangular in shape, while the lower and remaining portion of said hole forms a circular chamber or bore of different diameters, an extensible and retractable member extending entirely through and movable within the said hole, the upper portion of said member forming a handle of a rectangular-frame-shaped construction, while the lower and remaining portion of said member forms a shaft or spindle like projection movable within the circular portion of the hole, a spring encircling the spindle for normally retaining the handle within the ball, and a nut or button at the lower end of 75 the spindle.

15. A bowling-alley ball having, in combination, a hole extending axially entirely through said ball, an extensible and retractable member extending entirely through and 80 movable within said hole, a dovetail slot in the uppermost portion of said member, a bushing secured to said member and within the slot, a spring encircling the lower portion of the movable member for normally retaining said member within the ball, and a finger nut or button for raising the member and for limiting its outward movement.

In witness that I claim the improvements described in the foregoing specification I 90 have signed my name, in the presence of two subscribing witnesses, this 13th day of April, A. D. 1906.

CURTIS HOLLAND.
